US0D1004857S

(12) **United States Design Patent** (10) **Patent No.:** **US D1,004,857 S**
(45) **Date of Patent:** **** Nov. 14, 2023**

(54) **FRAME FOR PET IDENTIFICATION TAG**

(71) Applicant: **LG ELECTRONICS INC.**, Seoul (KR)

(72) Inventors: **Sungkyung Kim**, Seoul (KR); **Dongsoon Kim**, Seoul (KR); **Youngjee Son**, Seoul (KR)

(73) Assignee: **LG ELECTRONICS INC.**, Seoul (KR)

(**) Term: **15 Years**

(21) Appl. No.: **29/800,885**

(22) Filed: **Jul. 23, 2021**

(30) **Foreign Application Priority Data**

Jan. 29, 2021 (WO) WIPO101378

(51) **LOC (14) Cl.** **30-08**

(52) **U.S. Cl.** ..... **USPC D30/155**

CLAIM

We claim the ornamental design for a frame for pet identification tag, as shown and described.

DESCRIPTION

FIG. 1 is a perspective view of a frame for pet identification tag showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing a state of use thereof;

FIG. 9 is a perspective view showing a state of use thereof;

and,

FIG. 10 is a perspective view showing a state of use thereof. The broken lines in FIGS. 8, 9, and 10 illustrate environmental structure that form no part of the claimed design.

1 Claim, 10 Drawing Sheets
